UNITED STATES PATENT OFFICE.

RALPH G. JACKSON, OF CHESTER, PENNSYLVANIA, ASSIGNOR TO CONGOLEUM COMPANY, INCORPORATED, OF NEW YORK, N. Y., A CORPORATION OF NEW YORK.

PROCESS OF PRINTING AND MACHINE THEREFOR.

Application filed July 31, 1919. Serial No. 314,481.

To all whom it may concern:

Be it known that I, RALPH G. JACKSON, a citizen of the United States, and a resident of Chester, county of Delaware, State of Pennsylvania, have invented certain Improvements in Processes of Printing and Machines Therefor, of which the following is a specification.

My invention relates to certain improvements in flat block printing machines, in which a series of impressions are made to form a continuous design or pattern.

The object of my invention is to increase the production of such a machine without increasing the size of the block.

It is found in practice that a block 18" wide is the maximum width in which a block can be made for producing high grade printing. It has been the universal practice to feed the material intermittently the width of the block at each movement. These blocks are so arranged that different blocks print different colors on the same portion of the material so that one block will make an impression on the entire surface of the material consequently, the movement of the material is limited by the width of the blocks.

By my invention, however, I print on one section of the machine alternate spaces by one set of blocks and on the other portion of the machine I print the intervening space by another set of blocks. The two sets of blocks, where the design is a repeat, are similar and the colors are similar, so that the material can be moved a distance equal to twice the width of the block and, consequently, will travel through the machine at a greater speed than heretofore.

In the accompanying drawings:

Fig. 1 is a plan view illustrating in outline a flat block printing machine illustrating my invention;

Fig. 2 is a side view, also in outline, showing one of the essential parts of the machine;

Figs. 3 and 4 are diagrammatic views illustrating my improved method; and

Fig. 5 is a diagrammatic perspective view illustrating the material printed in accordance with my invention.

In Figs. 1 and 2 I have illustrated a machine for carrying out my invention. The general mechanism of the machine is of the type fully described in the patent granted to W. H. Waldron on the 25th of

December 1917, No. 1,251,144.

Referring to the drawings, 1 is the frame. 2 are the guides for the block carriers 3 on which are located the printing blocks 4. 5 are the cams on the shafts 6, which impart movement to the block carriers. These shafts 6 are driven from a longitudinal shaft 7 through suitable gearing. Latches 8 are provided for holding any of the block carriers out of action and mechanism, such as illustrated in the above mentioned Waldron patent, may be used for automatically operating these latches, if desired.

9, 9 are the mechanism for inking the block carriers and are reciprocated through means at one end of the machine so that when the blocks are raised the several inking mechanisms are traversed under their respective blocks and ink the printing surface thereof.

At each side of the machine are tapes 10, which pass around wheels 11 at each end of the machine and over the table 12 and the material to be printed is engaged by pins on these tapes in the ordinary manner. The wheels 11 at one end of the machine, as illustrated in Figs. 1 and 2, are mounted on a shaft 13 and loose on this shaft are two gear wheels 14 and 15. Between these two gear wheels is a clutch 16 splined to the shaft so that the clutch can engage either of the wheels 14 or 15 in order to impart a given movement to the tapes 10. The gear wheels 14 and 15 mesh with gear wheels 17 and 18, respectively, on a shaft 19 having a star wheel 20, which is intermittently rotated by a pin wheel 21 on a shaft 22 geared to the shaft 23 which, in turn, is driven from the longitudinal driving shaft 7 when the clutch 16 is in mesh with the gear wheel 14. Then the tapes 10 travel the ordinary distance, i. e., 18", but when the clutch is in mesh with the gear wheel 15 the tapes 10 travel 36".

By providing this clutch mechanism, the machine can be used for ordinary printing, i. e., in which the material travels 18", or it can be used for carrying out my improved process in which the material travels 36".

In the present instance, I have shown six printing blocks, three on one portion of the machine and three on the other portion of the machine. These blocks are 18" in width and are spaced 18" apart, but the space α between the two sets of blocks is 36" so that while the blocks a , a' , a'' print

the sections *d* of the material in three colors, the blocks *b*, *b'*, *b²* print in three colors on the spaces *e* of the material as clearly shown in Figs. 3, 4 and 5.

5 If the design be a continuous design, as illustrated in Fig. 5, then the design on each of the blocks *b*, *b'*, *b²* is similar to the design on the blocks *a*, *a'*, *a²*.

It will be noticed that where rugs are being printed, or a continuous material is being printed in which the alternate spaces are of a different design, then the blocks *b*, *b'*, *b²* differ in design from the blocks *a*, *a'*, *a²* and may also differ in color.

15 Thus it will be seen that while the blocks are of the standard width, the movement of the material is twice the width of the blocks, consequently, the production is considerably increased without increasing the speed, the 20 movement of the blocks, or the speed of the reciprocating movement of the inking mechanism, as the speed of the inking mechanism is limited, owing to the character of the ink or pigment.

25 While I have illustrated my invention as applied to a flat block printing machine, it will be noticed that the invention can be carried out in other types of printing machines, in which blocks or sections are used 30 for printing a given surface of material.

I claim:

1. The process herein described of printing material in a flat block printing machine, said process consisting in making a 35 series of impressions of a given width and spaced apart, the spaces being equal to the width of the impressions, then making a series of impressions on the spaces left blank by the previous printing, the designs of the 40 two sets of impressions being similar; and intermittently feeding the material a distance equal to the width of two blocks so that the impressions will make a continuous design.

2. The combination in a flat block printing machine, of two series of blocks equal in width, each series of blocks being spaced apart, the spaces being equal to the width of the blocks and the space between the two series of blocks being twice the width of a block; and means for intermittently feeding the material through the machine, each intermittent movement being equal to twice the width of the blocks so that the first complete impressions are spaced apart and the final impressions are made in the spaces between the first mentioned impressions.

3. The combination in a block printing machine, of a frame; a series of printing block carriers; means for operating the carriers; printing blocks mounted on the carriers, the carriers being arranged in two sections, the space between the sections being greater than the space between the blocks of each section; a power operated shaft; two 60 gears on said shaft; a shaft having wheels; and material-carrying bands arranged to travel over the wheels; two gears loose on the said shaft and differing in diameter; a clutch arranged to throw either of the gear 65 in engagement with the shaft so that when the clutch is in engagement with one gear, the material will move a distance equal to the width of the block and when the clutch is in engagement with the other gear the 70 material will be moved twice the distance of the width of the block.

4. A flat block linoleum or like printing machine having its blocks and color spaces of equal width and arranged in groups operatively separated by a distance equal to the width of two blocks or color spaces, and provided with feed mechanism for advancing the material a distance equal to the width of two blocks or color spaces at each 75 feed, substantially as described.

RALPH G. JACKSON.
